ROLLER STAND FOR SPINNING AND
PREPARING MACHINES

Joseph Noguera, Prestwich, Manchester, England, assignor to Casablanca's High Draft Company Limited, Salford, Manchester, England, a British company

Application April 9, 1946, Serial No. 660,712
In Great Britain April 19, 1945

6 Claims. (Cl. 19—134)

1

This invention relates to roller stands for supporting the drafting rollers of spinning and preparing machines.

In such machines, the drafting arrangement comprises a number of comparatively thin rollers which extend over the full length of the machine. The rollers are made up of short pieces coupled in series and supported at regular intervals by cast iron brackets known as roller stands, which are formed with or carry suitable bearings for the roller necks. The rollers are subject to intense torsional strain which tends to produce uneven revolution of the rollers resulting in uneven work and, in the extreme, breaking of the roller. It is therefore highly important if such defects are to be kept to a minimum, that the bearings of the roller stands are in alignment. This is not easy to achieve since even when the various roller stands are exactly alike, they are still liable to be out of alignment on account of mis-alignment of the roller beam to which they are secured, said beam being itself made up of a number of individual lengths. It has therefore become the custom to fit the roller stands individually with the aid of a line and to file the base of the stand or the underside of the middle and back bearings where necessary to bring the rollers into alignment.

The normal type of roller stand comprises two parts, a base which is secured to the roller beam and carries the front roller support, and a top part which is slidably supported upon an extension of the base and which carries the middle and back roller supports. It can readily be seen that to adjust the position of the various bearings of each of such stands so that they are correctly aligned on the machine, entails much slow and awkward work, especially in view of the fact that adjustment is only possible in the downward direction, by removing metal. The normal type of roller stand has a further consequent disadvantage in that it is not interchangeable and cannot be mass-produced.

Over and above the difficulties already explained, the alignment of the machine essentially depends upon the stability of the floor on which it rests, and will be disturbed by slight subsidences therein. Misalignment of the machine is therefore, in time, inevitable, and the machine must be realigned periodically, by filing either the bearings or the bases of the stands, where necessary, with the inherent risk of over-filing and returning a stand to use slightly lower than it should be.

The present invention seeks to provide a roller stand which avoids all the above mentioned diffi-

2

culties of adjustment and which will permit the roller bearings to be raised or lowered collectively, or the angle, which the plane of the rollers makes with the horizontal to be varied within any reasonable range required, in an extremely simple and accurate manner.

According to the invention, a roller stand comprises a base member adapted to be secured to a stationary part, and an upper roller supporting member which is so arranged for connection to said base member that it is capable of being held in positions of adjustment where it has been bodily approached to, or moved away from said base member, or where it has been tilted about either end, whereby the height or inclination of the plane of the rollers that may be carried by said roller supporting member, can be set as required.

In order to show how the invention may be carried into effect a constructional form thereof will now be described with reference to the accompanying drawings in which:

Figure 1 is a sectional side elevation of a roller stand;

Figure 2 is a corresponding front elevation;
Figure 3 is a section taken on the III—III line of Figure 1;

Figure 4 is a section on the line IV—IV of Figure 1;

Figure 5 is a plan view of a part of the roller stand, and

Figure 6 is also a similar plan view of another part of the stand with certain members removed for better illustration.

The adjustable roller stand shown in the drawings is one particularly applicable to ring-spinning mechanism, since the plane of the rollers supported by the stand is intended normally to be inclined downwardly towards the front roller. The roller stand as shown in the general assembly of Figure 1, essentially comprises a foot or base member 1 and a roller supporting member 2 carried thereby.

In Figure 5 there is shown a plan view of the foot member 1 and it will be observed that it includes a base plate 3 for connection with the roller beam 4 of the spinning frame. From Figure 1 it appears that the base plate 3 is held to the beam 4 by means of an anchor bolt. There is an upstanding approximately rectangular plate 5 formed integral with the base plate 3 and carrying an upwardly inclined limb 6. The limb 6 is of channel section and at its outer end has a pair of cheek members 7 and 8 which together form a yoke, the yoke being bridged by a portion 9. As seen in Figures 1 and 4, the two cheek

members 7 and 8 are apertured to receive a bolt 10 the head 11 of which fits into the cheek 8, in order to allow the head 11 of the bolt 10 to be turned, the head is formed with a shaped cavity 12 in which a suitable key may be introduced. The bolt is screwed into a ring nut 13 which fits as an immovable bush in the cheek member 7.

The bridge portion 9 has a horizontal bore which receives a plug 14 the latter being turnable within the bore of the bridge portion. The bridge portion 9 is also formed with a bore 15 at right angles to that first mentioned, and the plug 14 has a drilling 16 which may register with the bore 15, as shown in Figure 1. A link 17 is formed with screw-threaded portions 18 and 19, such portion 18 screwing within the bore 16 of the plug 14. The link 17 is formed with a slotted head 20 which permits it to be adjusted with for example a screw driver, in regard to its position within the plug 14.

The portion 5 of the foot or base member 1 has an arcuate slot 21 formed in it, such slot being centered about the axis of the bolt 10. Adjacent the slot 21 the portion 5 is formed with a horizontal bore receiving a plug 22 of the same type as the plug 14. In like manner, the plug 22 receives the threaded end of a link 23.

The upper part of the roller stand consisting of the roller bearing supporting member 2, is shown as a separate detail in plan view in Figure 6. From an inspection of both Figures 1 and 6 it will be realised that the member 2 consists essentially of a strip-like portion 24 formed at one end with a depending hook-piece 25 on which there is a plate 26 that enters a conveniently formed slot 27 in the foot member 1. The elbow 28 of the hook-piece 25 has a horizontal bore for reception of a plug 29 of the same character as the plug 14 previously described. The internally screw-threaded bore of the plug 29 has the screw-threaded portion 19 of the link 17 entered therein.

The strip-like part 24 of the roller bearing supporting member has two aligned slots 30 and 31 which as shown in Figure 1, serve to receive slider blocks 32 and 33 that respectively support the bearings for the back and intermediate rollers. The sliders 32 and 33 may be immobilised in any desired position by the fixing bolts 34 and 35. The front of the strip portion 24 is itself formed for the reception of the front roller bearing 36 and adjacent to the latter there is a horizontal bore housing a plug 37. The latter is the same as the plug 22 and serves to accommodate the head 38 of the link 23, such head being slotted to permit adjustment of the link with the aid of a screwdriver. The forward extremity of the strip-like portion 24 has a depending pair of cheeks 39 and 40 (see particularly Figures 2 and 3) which together form a yoke that embraces the upper end of the portion 5 of the foot member 1. The yoke serves to carry a bolt 41 having a head 42 of the same kind as that of the bolt 10 previously described. In like manner there is a cooperating nut 43 which is sunk into the cheek 39 and is immobilized therein as a bush. The bolt 41 passes through the arcuate slot 21 and is guided therein.

The depending plate 26 of the roller bearings supporting member 2, is formed with an arcuate slot 44. The latter is centered about the axis of the bolt 41 and the radius of the arc according to which the slot 44 is formed, is the same as that applying to the arcuate slot 21.

From the description above it will be realised

that when the bolts 41 and 10 are slack, the links 23 and 17 may be rotated by means of their heads 38 and 20. The screw-threadings of each end of each link are relatively opposite, that is to say if the screw thread is right-hand at one end of a link, then the screw thread at the other end thereof is lefthand. Thus if, say, the link 23 be turned in one direction, then it will cause one end of the member 2 to be approached towards the adjacent end of the foot member 1. If the link 23 be turned in the opposite direction, then the appropriate end of the member 2 will rise away from the adjacent end of the member 1. The same remarks apply to the link 17, and it will be realised that the member 2 may be adjusted relatively to the foot member 1, so as to lift the member 2 bodily, or alternatively to swing the same about either end of its pivotal fixation by the links 17 and 23. In this way the roller bearing supporting member can as a whole be adjusted for height, and can be adjusted to any desired inclination in either direction.

When the bearing supporting member 2 has been brought to the desired position of adjustment by means of the links 17 and 23, it may be immovably held in that position by tightening the bolts 41 and 10. It will be of interest to note that because of the radius at which the arcuate slots 44 and 21 are made, slight translational movements of the member 2 will compensate for the varying positions which the bolts 41 and 10 may occupy in the arcuate slots. The translational movements will be so small as to be negligible for the reason that the radius in question is fairly great and the extent of the translational movements will depend upon the greatest radial distance which exists between the chord joining either extremity of the arc, and the arc itself. Since the distance along the curved arc is in each case extremely small and the radius relatively great, the greatest radial distance between the arc and the chord is extremely small. It will of course be appreciated that if it were not desired to make the slots 21 and 44 arcuate, then it would be necessary to allow a certain amount of slack as between the bolts 41 and 10 and their respective slots. This slack is unnecessary in the employment of the arcuate slots described and shown.

The degree of adjustment which may be obtained with a roller stand made in accordance with the description above, is incomparably greater than is possible with existing forms of roller stands. Moreover, the roller stand of the invention permits great accuracy in the setting operation, whilst this operation is reduced to one of great simplicity.

At first sight, it may be considered that the construction of roller stand following the principles of the invention, is somewhat more elaborate than usual. The cost of production of the stand can be kept, however, within reasonable limits by die-casting the same. The bearings for the rollers can then be formed with adequate housings fitted with a sleeve made of good bearing metal such as phosphor bronze. A removable sleeve of this kind is shown at 36 in Figure 1, and it will be realised that when the bearing sleeves are worn they can be easily and cheaply replaced. The sleeves may advantageously be formed of porous metal which retains oil and would thus require only infrequent lubrication.

Roller stands made in accordance with the invention, can be interchanged within a machine

which in itself represents a highly desirable feature.

The existence of the channel section portion 6 in the foot or base member 1, provides a convenient space for accommodation of the supporting and adjusting mechanism for the bars of what is known as the Casablanca automatic lever weighting.

I claim:

1. A roller stand for spinning and preparing machines comprising a base member for attachment to a stationary part of the machine, an upper roller supporting member, a pivotal connection between each end of said supporting member and said base member and adjusting means associated with each said pivotal connection for adjusting the height and inclination of said supporting member with respect to said base member.

2. A roller stand for spinning and preparing machines comprising a base member for attachment to a stationary part of the machine, a projecting limb formed on said base member, an upper roller supporting member co-extensive with said limb, two pin and slot mechanisms respectively for pivotally connecting each end of said supporting member to each end of said limb and an adjustable link member adjacent each said pivotal connection, said link members being operable independently to adjust the position of said supporting member with respect to said limb.

3. A roller stand for spinning and preparing machines comprising a base member for attachment to a stationary part of the machine, a projecting limb on said base member, an upper roller supporting member co-extensive with said limb, a pin carried at one end of said supporting member, a further pin carried at the opposite end of said limb, said pins engaging in arcuate slots in said limb and supporting member respectively, the slot in one member being centred about the pin in the same member and said slots having the same radius of curvature and adjusting means associated with each said pin and slot said adjusting means being operable independently to adjust the position of said supporting member with respect to said limb.

4. A roller stand as claimed in claim 2 further

comprising plugs turnably mounted adjacent each end of said limb and said supporting member, said plugs having screw-threaded bores therein for receiving opposite ends of said link members.

5. A roller stand for spinning and preparing machines comprising a base member for attaching to a stationary part of the machine, a projecting limb on said base member, a slotted upper roller supporting member co-extensive with said limb and formed for reception of the front roller, bearing blocks slidably mounted in said slots in the supporting member for reception of intermediate and back roller bearings, a pivotal connection between each end of said supporting member and said limb and adjusting means associated with each said pivotal connection, said adjusting means being operable independently to adjust the height and inclination of said supporting member with respect to said limb.
- 10 6. A roller stand for spinning and preparing machines comprising a base member, a foot on said base member for attaching to a stationary part of the machine, an upper roller supporting member, a projecting limb partially of channel section, substantially co-extensive with said roller supporting member, a pivotal connection consisting of a pin and arcuate slot mechanism between each end of said supporting member and said projecting limb and adjusting means associated with each said pivotal connection, said adjusting means being operable independently to adjust the height and inclination of said supporting member with respect to said limb.
